(57) **CLAIM**

What is claimed is the ornamental design of a bottle, as shown and described.

DESCRIPTION

FIG. 1 is a perspective view of a bottle of our new design.

FIG. 2 is a front elevation of the bottle of FIG. 1.

FIG. 3 is a rear elevation of the bottle of FIG. 1.

FIG. 4 is a top plan view of the bottle of FIG. 1.

FIG. 5 is a bottom plan view of the bottle of FIG. 1.

FIG. 6 is a perspective view of a further embodiment of a bottle or our new design.

FIG. 7 is a front elevation of the bottle of FIG. 6.

FIG. 8 is a rear elevation of the bottle of FIG. 6.

FIG. 9 is a top plan view of the bottle of FIG. 6.

FIG. 10 is a bottom plan view of the bottle of FIG. 6.

FIG. 11 is a perspective view of a further embodiment of a bottle or our new design.

FIG. 12 is a front elevation of the bottle of FIG. 11.

FIG. 13 is a rear elevation of the bottle of FIG. 11.

FIG. 14 is a top plan view of the bottle of FIG. 11.

FIG. 15 is a bottom plan view of the bottle of FIG. 11.

FIG. 16 is a perspective view of a further embodiment of a bottle or our new design.

FIG. 17 is a front elevation of the bottle of FIG. 16.

FIG. 18 is a rear elevation of the bottle of FIG. 16.

FIG. 19 is a top plan view of the bottle of FIG. 16; and,

FIG. 20 is a bottom plan view of the bottle of FIG. 16.

The broken line showing of the bottle is included for the purpose of illustrating portions of the bottle and forms no part of the claimed design.
